UNITED STATES PATENT OFFICE

JOHN S. SKOGLUND AND CHRISTIAN M. ENGEBRETSON, OF STARBUCK, MINNESOTA

ROOF-SEAMING STRIP

Application filed December 12, 1924, Serial No. 755,447. Renewed January 6, 1930.

This invention relates to improvements in roofing devices and has for its object to provide a joint cleat for strips of roofing material.

5 Another object of the invention is to provide a connecting and retaining cleat for seams of flexible roofing materials.

A still further object of the invention is to provide a combined seaming cleat and 10 straight edge for the joints of flexible roofing materials.

A still further object of the invention is to provide an attachable watertight joint or seam for flexible roofing materials.

15 With the above and such other objects in view as may hereinafter more fully appear, we have invented the device illustrated in the accompanying drawings in which:

Figure 1 is a plan view of a section of 20 roofing embracing our invention;

Figure 2 is a perspective view thereof, shown partly in section.

Like reference characters indicate like 25 parts throughout the following specification and in the several views in the drawings in which 1 indicates a roofing upon the sheathing 2 on which is laid a roofing material 3 formed in sections 3' and 3^a, the edges 4 and 5 of said sections being joined and seamed by 30 means of a seaming strip 6, formed of sheet metal and being substantially S-shaped in cross section providing three layers 7, 8 and 9, the bottom layer 7 of which is flat and the intermediate layer 8 is substantially flat,

35 while the edge 10 of the upper layer is flat and its intermediate portion 11 is concavo-convex, its free edge 12 is curved terminating in an angular flange 14 which, when driven into its place upon the edge 4 of the 40 member 3', bends a longitudinal corner 15, forcing it down over the connecting bend 16 between the layers 7 and 8 of the strip 6.

A series of longitudinally spaced apart 45 apertures 17 are provided at the apex portion of the convex rib 11, through which the nails 18 are driven. The other layers 7 and 8 of the strip 6 are imperforate prior to use thereof.

In operation the underlayer 7 of the strip 50 6 is projected under the edge 5 of the roof-

ing layer 3^a until said edge is seated wholly within the groove 19 formed by the layers 7 and 8. The upper layer 9 is normally spaced sufficiently far from the layer 8 to readily receive the edge 4 of the roofing layer 3' into 51 the groove 20, formed between the layers 8 and 9 of the strip. The inner or side wall of the groove 20 is formed at right angles to the layers 8 and 9 and forms a straight edge against which the terminal edge of the layer 60 of roofing material to be seated therein is adapted to seat, the groove 20 also forming means for regulating the overlap of the roofing layer 3'. After this operation is completed the layer 9 is pressed down into place 65 upon the said edge 4 and the nails 18 projected through the aperture 17 and then driven home, the concavo-convex form of the rib 11 causing the edge 14 of the layer 9 to bind tightly against said edge 4, thus making 70 a perfect watertight seam connection between the layers 3' and 3^a of the roofing material without the application of cement or other binder than the strip 6. The nails 18 are preferably provided with corrugated shanks 18' in order that when driven through 75 the layers 8 and 7 respectively, said corrugations will be engaged by the edges of the perforations formed by said nails and prevent the withdrawals of the nails even in 80 case the nails should happen to come between sheathing boards.

Having described our invention that which we claim to be new and desire to procure by Letters Patent is:

85 A securing strip for the edge portions of overlapping roofing sheets consisting of a sheet of metal bent S-shaped in cross section forming three overlapping layers co-acting to provide a pair of opposing channels to receive said edge portions, the top layer of the strip being convex and having its free edge projecting downwardly beyond the lower channel whereby a tight joint is obtained.

90 In testimony whereof we affix our signatures.

JOHN S. SKOGLUND.
CHRISTIAN M. ENGEBRETSON.
